BAR OF SOAP OR SIMILAR ARTICLE

Frederick J. Zeityogel, Makati, Rizal, Republic of the Philippines, assignor to Colgate-Palmolive Company, New York, N.Y., a corporation of Delaware

Filed June 15, 1966, Ser. No. 2,688

Claims priority, application Republic of the Philippines
Dec. 29, 1965

Term of patent 14 years

(Cl. D73—1)

FIG. 1

FIG. 2

FIG. 4

FIG. 1 is a perspective view of a bar of soap or similar article embodying my new design and showing the front face, top and one end thereof;

FIG. 2 is a rear elevational view of my bar of soap or similar article as seen from the face not visible in FIG. 1;

FIG. 3 is a side elevational view of my bar of soap or similar article as seen from the side not visible in FIG. 1; and

FIG. 4 is a bottom plan view thereof.

I claim:

The ornamental design for a bar of soap or similar article, as shown and described.
